ATTORNEYS.

UNITED STATES PATENT OFFICE.

WALTER D. EASTBURN, OF ELKINS PARK, PENNSYLVANIA.

FOLDING SEAT.

Application filed October 30, 1926. Serial No. 145,149.

My invention relates to a new and useful folding seat, and more particularly, to a folding seat of the general character adapted to be used in breakfast rooms, commonly known as "breakfast nooks", school lunch rooms, cafeterias and other situations, wherever space is limited, as is frequently the case in modern dwellings, apartment houses, school rooms and the like.

10 In folding seats or chair constructions known and used heretofore, it has frequently been the practice pivotally to secure the seat member to the support thereof, so that when the seat was not in use, it could be 15 folded upwardly and backwardly into a substantially vertical position against the upright back of the support. In constructions of this general character, the principal result accomplished was that of facilitating 20 passage between the successive rows of seats or chairs when such seat supports were fixed, as is the case in theaters and the like or to facilitate the packing and moving around of such seats or chairs when the latter were 25 not stationary or permanently fixed to the floor. In the former case, the chairs or seats occupied a certain amount of floor space at all times, while in the latter case, if it was desired to utilize the floor space for some 30 other purpose, it was necessary to remove the chairs or seats to some other place for temporary storage, all of which was inconvenient and consumed considerable time and labor. It is therefore obvious that neither 35 of these or similar constructions could be advantageously used where space is very limited, or where the number of chairs or seats needed is very large, all of which made the use of such prior devices somewhat un- 40 desirable.

Another expedient heretofore resorted to was that of folding chairs or seats built-in, in the wall of a room and adapted to be used in connection with tables and the like, so that 45 when such chairs were not in use, the same could be folded back against, and would seat in a recess in such wall or other surface to which they were secured. While this construction economized floor space, yet it was 50 disadvantageous in that the use of such chairs or seats was necessarily confined to the particular place or point at which such chairs were permanently secured.

To obviate the above disadvantages, my

invention is designed to provide folding seats to be used in connection with tables, desks, counters and the like, which will occupy a minimum amount of space when in use and which will occupy no additional space whatever when not in use, or when in the folded position, affording at the same time a comfortable and convenient individual seat when in the unfolded position.

Another object of my invention is to provide a folding seat, which is adapted to be secured to the table, counter, or the like, in conjunction with which such seat is to be used, and to be folded thereunder, thus producing a unitary structure which may be transported at will and one which will occupy no more space than that required for the accommodation of tables and counters of any conventional construction.

A further object of my invention is to produce a folding seat of this general character, which can be deflected into and withdrawn from the operative or seating position, easily and quickly, with but a single movement and one which can be manufactured at a minimum cost, spring pressed friction devices being provided to retain the seat and its adjuncts in folded position and to retard the movement of the parts to the proper extent when the seat and its adjuncts are moved from the folded to the unfolded position.

For the purpose of illustrating my invention, I have shown in the accompanying drawings, a form thereof which is at present preferred by me since it will give in practice satisfactory and reliable results, although it is to be understood that the various instrumentalities of which my invention consists can be variously arranged and organized and that my invention is not limited to the precise arrangement and organization of these instrumentalities as herein shown and described.

In the accompanying drawings:

Figure 1 represents a side elevation of folding seat embodying my invention, and a portion of a table to which the same is applied, the seat and its adjuncts being shown in full lines in the operative or seating position and in dotted lines in the folded or inoperative position.

Figure 2 represents an end elevation of Figure 1.

Figure 3 represents a top plan view, part

ly in section, on line 3—3 of Figure 1, showing the pivoted mechanism and the friction devices employed.

Figure 4 represents a vertical section on line 4—4 of Figure 3.

Referring to the drawings, in which like reference characters indicate like parts, 1 designates a table equipped with a folding seat embodying my invention, comprising the supporting pedestal 2, the top 3 and the legs 4, which may be of any conventional construction. To each of the outwardly projecting legs 4, is pivotally secured the folding seat structure 5 of my novel construction, as will be clearly seen in Figs. 1 and 2. 6 designates a casing, secured to and enclosing the outer end of the leg 4, by means of the screws or other fastening means 7. 9 designates a lug on the top plate 8 of the casing 6, to which is pivoted the inner end of the link 10 which may be a pipe or rod or the like, the outer end of which is pivotally secured to the horizontal arm 11 by the bolt 12, said arm 11 being integral with or permanently secured to the vertical support 13 for the seat 14. At a suitable point below the arm 11, the support 13 is provided with the legs 15, which may be made integral therewith or permanently secured thereto, and which support the folding seat structure 5, when the latter is in the extended or seating position shown in full lines in Fig. 1. To the outer or end plate 16 of the casing 6 is secured the ears 18, to which is pivotally secured the elongated frame or housing 19 by means of the bolt 33, said housing 19 comprising the side walls 20 and the bottom and top walls 21 and 22 respectively, the outer end of said housing being pivotally secured 40 to the vertical seat support 13 by the bolt 23, as will be understood from Fig. 1. Enclosed in the housing 19, shown in Fig. 3, the top wall 22 being shown broken away for a portion of its length, is the transverse wall 24 through which extends the outer threaded end 26 of the rod 25, which carries the tension spring 27. The front end of the spring 27 abuts against a washer held in position by the nut 28, while the inner end 50 of said spring bears against the rear transverse wall 29 through which extends the inner end 30 of said rod 25, to which end 30 is pivotally secured the bracket composed of the plates 31 by the bolt 31, said plates 31 carrying at their innermost ends, the rollers 32, which bear against the inner curved surface or cam face of the cam 17, which is fixedly secured to the casing 6, as will be understood from Fig. 4. The tension spring 60 27, causes the rollers 32 frictionally to engage at all times, the inner surface of the cam 17, so as slightly to retard the downward movement of the housing 19, and its adjuncts and in addition, retains the seat

structure 5 and its adjuncts, in folded position.

Thus, when it is desired to use my novel folding seat, it is only necessary to pull the same outwardly from the vertical, folded or inoperative position shown in dotted lines in Fig. 1, to the operative or seating position indicated in full lines in the same figure. When on the other hand it is desired to fold the seat back out of the seating position, it is only necessary to push the same upwardly back into the vertical, inoperative position, as will be understood from Fig. 1, in which position the seat will occupy no room whatever, and in which position the table and the several seats thus secured thereto may be moved from place to place a unit. It will be noted that I so shape the link 10, that when the seat is in the operative or seating position, said link will be in a relatively low horizontal position thus facilitating the use of my novel folding seat by women and children and affording, at the same time, a convenient foot rest or stool.

The spring 27 constantly urges the rollers 32 outwardly against the inner surface of the cam member 17, and thus counterbalances the weight of the seat 5 and its adjuncts, and prevents the same from moving too rapidly from the vertical folded position, when said seat is being drawn to seating position or when the table is being moved about, and renders the movement of the seat in the folding and unfolding operation smooth and even.

While in the accompanying drawings I have, for the purpose of illustration, shown my novel folding seat applied to the legs 4 of a pedestal table, it will be understood that by slightly modifying the form of the casing 6, as for example by substituting a flanged plate or bracket therefor, I can secure my novel folding seat 5 to the floor of the room at suitable intervals around the sides of a table, or to the wall behind, or the rear wall of, a shelf, counter or the like, thus producing a folding seat that may be used in connection with any such article of furniture or fixture and one which may be used in a fixed or movable position at will. It will further be seen that I have devised a durable, folding chair of universal use and applicability, which can be manufactured and assembled at a minimum cost.

It will now be apparent that I have devised a novel and useful folding seat which embodies the features of advantage enumerated as desirable in the statement of the invention and the above description and while I have, in the present instance shown and described an embodiment thereof which is at present preferred by me since it will give in practice satisfactory and reliable results, it is to be understood that such embodiment is

susceptible of variation in various particulars without departing from the spirit or scope of the invention or sacrificing any of its advantages.

5 Having thus described my invention what I claim as new and desire to secure by Letters Patent, is:—

10 1. The combination of a seat pivotally supported, means for folding said seat inwardly into vertical, inoperative position and for unfolding said seat outwardly into seating position and means to retain said seat in vertical folded, inoperative position against dropping outwardly when the latter 15 is not in use, comprising a fixed inner cam surface, rollers bearing on said cam surface, a support for said rollers pivotally connected to the seat support, having means therein for imparting tension to said rollers, to counterbalance the weight of the said seat and its adjuncts.

20 2. In a folding device of the character stated, a seat, a support therefor, an upper link having its outer end pivotally secured to said seat support and its inner end pivot 25 to a fixed point, a lower housing having the outer end thereof also pivotally secured to said seat support, and its inner end pivot 30 to a fixed point, a fixed cam, rollers carried by said lower housing and bearing against said cam and yieldable means in said housing adapted to tension said rollers against said cam to counterbalance the weight of said seat when 35 the latter is in folded position, said pivotal means at the inner ends of said link and housing respectively enabling the two latter to be detachably secured to any desired fixed point.

40 3. In a device of the character stated, a seat, a vertically disposed support therefor, a relatively fixed rear member, a link having its rear end pivoted to said fixed member, and its front end pivotally connected to said 45 seat support, an elongated frame below said link and having its front end pivotally secured to said seat support, and its rear end also pivoted to said fixed member, a fixed inner cam surface carried by said fixed member, rollers carried by the rear end of said frame and frictionally engaging said cam surface and means in said elongated frame for imparting tension to said rollers, to

counterbalance the weight of said seat and its adjuncts. 55

4. In a device of the character stated, a table, a support therefor, a folding seat adapted to be folded inwardly into a vertical, inoperative position beneath said table and to be unfolded outwardly into a seating 60 position with respect thereto, a support for said seat, a lower housing having its inner and outer ends pivotally secured to said table and seat supports respectively, an upper link having its inner and outer ends also pivotally secured to said table and seat supports respectively to limit the inward movement of said seat, when the latter is folded into vertical, inoperative position, a fixed cam carried by said table, rollers carried by the 65 inner end of said housing and frictionally engaging said cam, and yieldable means in said housing, adapted to tension said rollers against the inner surface of said cam to counterbalance the weight of said seat and to 70 prevent the same from dropping from vertical, folded, inoperative position, said seat and said table being movable as a unit. 75

5. In a device of the character stated, a seat, a vertical support therefor, an upper link having its outer end pivoted to said seat support, a lower housing having its outer end also pivoted to said seat support, a relatively fixed member to which the inner ends of said link and housing are pivoted, the front and rear pivotal points of said link and housing being out of alignment, a fixed cam carried by said fixed member, rollers carried by the rear end of said housing bearing on said cam, and tension devices in said 85 housing for retaining said rollers in contact with said cam, to counterbalance the weight 90 of said seat and its adjuncts.

6. In a device of the character stated, a seat, a seat support, legs carried by the latter, an upper link, a lower housing, said link and housing having their front ends pivoted to said seat support and their lower ends pivoted to relatively fixed points, said front and rear pivotal points being out of alignment, a fixed cam, rollers carried by the rear end of said housing bearing on said cam and means in said housing for tensioning said rollers against said cam to counterbalance the weight of said seat and its adjuncts. 95 100
